Charles Kane

United States Patent Office.

CHARLES KANE, OF PITTSBURG, PENNSYLVANIA.

Letters Patent No. 73,728, dated January 28, 1868; antedated January 16, 1868.

IMPROVEMENT IN DIES FOR HEADING BOLTS.

The Schedule referred to in these Letters Patent and making part of the same.

TO ALL WHOM IT MAY CONCERN:

Be it known that I, CHARLES KANE, of the city of Pittsburg, in the county of Allegheny, and State of Pennsylvania, have invented certain Improvements in Ledge-Dies for Staving Bolts; and I do hereby declare that the following is a full and exact description thereof, reference being had to the accompanying drawings, and to the letters of reference marked thereon, in which—

Figure 1 is a view of the face of one of my improved dies, and die with which it is combined.

Figure 2 is an oblique geometrical view of my dies, seen from the side.

Figure 3 is a view of the face of the common ledge-die; and

Figures 4, 5, and 6 are views of my improved ledge-dies, illustrating their working.

This invention relates to that class of dies having a ledge or shelf used for confining the iron in the process of gripping and staving bolts, and it consists in the peculiar shape of the ledge, as hereafter described.

To enable others skilled in the art to make and use my invention, I will proceed to describe its construction and operation.

A is the ordinary half round gripping-die, which I use in connection with my improved dies. B and C are my improved dies, which are made as ordinary ledge-dies, so far as regards their face, D, which is perpendicular to the plane of motion of the die, but which have a ledge of a different form than the one hitherto made, and which operate in such a manner as to form a better bolt. The face of my improved ledge, which serves the purpose of keeping the iron from spreading during the process of staving and gripping, is a plane surface, parallel to the line of motion of the dies in the direction of said movement, but forming an angle with said line of motion, if measured in a right-angle direction with it, so that when the dies are brought together the space left between them will be the same width all over, if measured horizontally from f to g and from h to t; but if measured vertically, will be greater from h to e and t to P, than from f to M and g to s.

The object of this construction is illustrated in my figs. 4, 5, and 6; where fig. 4 represents the iron during its first operation, fig. 5 represents the position in which the iron is turned before the second operation, and fig. 6 illustrates the action of a second pressure of the gripping-dies on the iron.

It is easily understood by those skilled in the art of staving bolts, that the additional amount of metal which my dies allow to expand near the place where the shape of the bolt is changed from round to square, will enable me to obtain much sharper and better-defined corners to that part, and a much handsomer bolt.

Disclaiming any novelty in any part of what I have described, which is not my intention to claim—

What I do claim as my invention, and desire to secure by Letters Patent of the United States, as my improvement in bolt-pressing and staving machinery, is—

The inclining of the plane of the ledges in the direction of the gripping-dies, and from the axis of the bolt, in combination with pressing surfaces parallel to the axis of the bolt, as specified.

CHARLES KANE.
